UNITED STATES PATENT OFFICE.

JOSEPH ROYLANCE, OF SAN FRANCISCO, CALIFORNIA.

STOP-VALVE.

SPECIFICATION forming part of Letters Patent No. 259,426, dated June 13, 1882.

Application filed January 18, 1882. (No model.)

To all whom it may concern:

Be it known that I, JOSEPH ROYLANCE, of the city and county of San Francisco, in the State of California, have made and invented 5 a new and useful Improvement in Stop-Valves; and I do hereby declare that the following is a full, clear, and exact description of the same, reference being had to the accompanying drawings.

10 My invention relates to stop-valves for steam, water, and other pipes, and of the class or kind in which the gate or valve has a sliding movement into and out of its chamber, and also a lateral movement against the valve-seats, when 15 it is lowered or moved into position across the opening or passage through the valve.

My improvement consists in a certain novel construction of valve-operating device, in manner substantially as hereinafter described, and 20 the combination thereof with the valve body or chamber and the valve-stem or lifting device, by which I produce an improved stop-valve.

Referring to the accompanying drawings, 25 Figure 1 is a longitudinal section through the body or chamber of the valve, showing the position of the valve or gate and its operating mechanism when the water-way or passage through the body is closed. Fig. 2 is a horizontal section through the body or chamber. 30 Figs. 3 and 4 are details of the gate or valve, the screw-stem, and the device connected with and operated by the stem for moving the valve laterally against and holding its bearing-surfaces tightly to the seats around the opening. 35 Fig. 5 is a view of this operating device with the valve-disks or bearing-surfaces removed.

A is the valve body or chamber, of the usual construction, with the box or upper compartment, B, into which the gate or valve when raised is received, for the purpose of providing a clear unobstructed water-way or passage through the chamber; and C is the screw-stem by which the gate or valve is raised and lowered. This gate or valve D is formed of two disks or bearing-surfaces, e e, placed on opposite sides of a square-faced nut or block, f, traveling on the screw-threaded portion of the stem, and carried by it up and down or out 45 of and into the chamber of the valve. These disks are not permanently fixed to the block

f, but they are loosely attached to it, so that while being moved up and down or into and out of the passage or water-way they are also free to be moved laterally outward and closed 55 tightly against the seats g. To attach the disks to the block f in this manner, I employ a short stud or dowel, h, on the inner face of the disk, and a hole, i, to receive it in that end of the block against which the disk is placed. 60 This projection h is long enough to enter and be retained in the hole i during all the movements of the disk, whether in sliding into and out of position or in being moved laterally to bear against and close tightly on the seats g; 65 and where these disks or bearing-surfaces are made circular in form, as in the present construction, I locate this projection h in the center of the inner face, so as to permit the disk to turn and be rotated upon it, and thus 70 change the face with respect to the valve-seat g to prevent irregular wear; also, where a single projection is used, it is made of suitable diameter or thickness to support the disk and keep it from sagging or dropping down 75 at one side, or otherwise getting out of line or position with respect to the seat g. Several of these dowels h may be used where the bearing-surfaces e are larger or of oblong shape.

To move and hold the disks e against the 80 seats g, I employ the double-acting levers pp, which are pivoted to and carried by the block f in such manner that at the downward movement of the gate or valve into position to close the opening through the chamber the lower 85 ends of each set of the levers are brought astride of and pressed against a stationary wedge or stop, m, fixed on the bottom of the chamber with sufficient force to spread the ends of the levers apart. Each set of these 90 levers forms a cross, and is held to the side of the block by a short pin or pivot-bolt, k, and so placed between the two disks or bearing-surfaces of the valve that while the upper end of one arm or member of the set bears against 95 the back of the disk at one side the lower end of the same arm is against the lower portion of the other disk. The outer ends of these arms are cut off square, or formed with a flat surface, to coincide with the plane of the disks 100 against which they rest, and being thus confined between the two disks, these levers will

act to spread them apart in a regular manner, equally at top and bottom, whenever any object (as a wedge) is forced in between the crossed arms or members constituting the lever. For this purpose I fix on the bottom of the chamber, beneath the screw-stem, the fixed wedge or block *m*, and by means of the screw-stem bring the gate or valve down into place between the two seats *g*, and at the same time produce the lateral movement or spreading apart of the disks *e*. The gate is fitted into the chamber of the valve, so that the amount of lateral pressure of the disks required is very small, and this construction affords a simple holding device having great power and a rapid action. The disks or bearing-surfaces of the gate are readily taken out and renewed when worn.

Having thus fully described my invention, what I claim, and desire to secure by Letters Patent, is—

1. The sliding gate or stop-valve consisting of the block *f*, traveling on and adapted to be moved by the valve-stem, the crossed levers carried by and pivoted to the said block, the disks or bearing-surfaces *e e*, having the ends of the said levers resting against and bearing

on their inner faces, and means for spreading apart or extending the said levers when the gate or valve is in position between the valve-seats of the valve-chamber, substantially as described, to operate as set forth.

2. The combination, with the disks or bearing-surfaces *e e*, attached to the traveling block *f*, of the crossed levers *p p*, pivoted to the sides of the said block, and the wedge or projection *m*, adapted to spread apart and extend the said levers by the movement of the block *f*, substantially as described.

3. The improved valve consisting of the body *A*, with the way or passage having the seats *g*, the valve-stem, the block *f*, operated by said stem, as described, the disks or bearing-surfaces *e e*, loosely attached to and carried by said block, and the crossed levers *p* and the fixed stop or projection *m* within the chamber, forming the means for moving the bearing-surfaces against and holding them to the valve-seats *g*.
